UNITED STATES PATENT OFFICE.

JACOB G. CROOKSTON, OF PITTSBURGH, PENNSYLVANIA.

SAFETY RAZOR.

Application filed March 14, 1923. Serial No. 624,970.

This invention relates to safety razors of the type in which a double-edged blade is flexed transversely when clamped in the holder.

5 The closest shave obtainable is afforded by the old style straight razor with unprotected blade, because the cutting edge is there freely presented against the face with no impeding or interfering means. The care and skill required in using such a razor in order to prevent cutting or abrading the face has been responsible, to a large extent, for the development of safety razors in which the cutting edges of the blades are protected by 10 guards extending slightly beyond the cutting edges. The maximum safety from a razor of this type is afforded when the teeth of the guard are flush with the cutting edge of the blade. However, experience has 15 proven that such an arrangement is not fully satisfactory, because the guard teeth, lying flush against the cutting edge of the blade, blank a considerable portion of the cutting edge, thus rendering that portion of the cutting edge useless for shaving purposes. Also, this arrangement causes irritation of the face by reason of the beard lodging between the razor blade and guard teeth without being 20 freely cut from the face.

25 To obviate as far as possible these and other disadvantages incident to prior safety razors of the type contemplated by this invention, and to more nearly approximate the close shaving advantages of the old style straight razor, it has been the practice to 30 loosen the blade clamping means and thus permit the edge of the blade to spring away from the guard. It is obvious that as the cutting edge of the blade recedes from the 35 face of the guard, the cutting action is improved and the safety feature diminished, even to the point of being eliminated entirely as the cutting action approximates that afforded by an unguarded straight razor blade.

40 In fact, I have learned by experiments and study that use of a safety razor of this type, adjusted for a close shave with the blade free above the guard, results in numerous cuts and abrasions of the face of the user.

45 because he is, without realizing it, using an unprotected blade as recklessly and carelessly as he has learned by experience that he can use a protected blade.

Such cuts and abrasions are mostly, if not entirely, caused by the exposed corners of the cutting edges of the blade. The pres-

sure on the razor when shaving causes the blade to press against and to slightly depress the skin over which it passes, and at the ends of the relatively short cutting edge 60 slight ridges are formed in the skin, so that slight unsteadiness of the hand holding the razor will cause an end of the cutting edge to impinge against the ridge of skin adjacent to it and thus result in cutting or abrading the skin. Between the ends or corners of the cutting edge, this condition does not arise because the skin is uniformly depressed by the cutting edge of the blade. 65

An object of my invention is to provide 70 a simply constructed safety razor of the double-edged flexed blade type, in the use of which the shaving action closely approaches, if not entirely realizes, that afforded by the old style unprotected straight blade razor, 75 and which is constructed to effectively guard against cuts and abrasions.

A further and more specific object is to provide 80 a safety razor of the type stated, in which there is an unobstructed passage and chamber to receive shaving refuse, and which is further constructed to facilitate removal of such refuse.

A still further and more specific object 85 is to provide a safety razor of the type stated, in which the corners of a blade are held rigidly against the guard member, and the guard member spaced from the blade intermediate its ends, whereby the edges of the blade are free to effect satisfactory shaving without liability of cutting or abrading the skin of a user. 90

A further object is to provide an efficient foldable safety razor which is so simple in construction that it may be economically 95 manufactured, and which may be quickly assembled and disassembled.

Other objects will appear in the ensuing 100 description of the invention.

In the accompanying drawings the invention is illustrated in its applicability to two types of safety razors, one the type in which a single handle projects from the center of the razor, and the other the type in which a pair of handles are pivotally 105 attached to the ends of the razor and when not in use are adapted to fold upon the razor. Fig. 1 is an end view and Fig. 2 a side view of the first mentioned type of razor; Fig. 3 a transverse sectional view taken on the line III—III, Fig. 2; Fig. 4 a side view of the foldable type of safety 110

razor, one of the handles being folded upon the razor and the other being moved to the position it occupies when the razor is in use; Fig. 5 a plan view of the clamping plate 5 and attached handles of the razor of Fig. 4; and Fig. 6 a plan view of the guard plate of the razor of Fig. 4.

Having reference first to the razor of Figs. 1, 2, and 3, it comprises guard 1, a clamping plate 2, a handle 3 provided with a threaded socket to receive a threaded pin 4 attached to the center of the clamping plate, and a blade 5 of the double-edged transversely flexed type arranged between the clamping 15 and guard plates.

In the practice of the invention, the guard plate 1 has guard teeth 6 formed on both of its edges and is provided at its corners with tongues 7 which project above the plane 20 of the guard teeth and form supports for the corners of the blade. The guard plate is preferably, although not necessarily, flat and is provided at its central portion with a relatively abrupt projection 8 on which 25 the central portion of the blade rests, and about which the blade is transversely flexed when clamped between the guard and clamping plates. The tongues 6, in addition to affording supports for the corners of the 30 blade, project slightly beyond the ends of the blade so that its corners are blanked against cutting action, and hence cannot cut or abrade the face of a user in the manner previously explained. Between the tongues 35 6 the guard is uniformly depressed below the plane of the tongues, with the result that the blade is free to cut in substantially the same effective manner as ordinary razors which are not provided with guards. Furthermore, between the blade and the 40 depressed guard, there is formed a clear passageway for shaving refuse which may collect on each side of the razor in a chamber formed by the guard plate, blade and projection 8. These chambers are opened at 45 both ends as well as at their sides so that water may be flushed through the razor to quickly and effectively remove the shaving refuse.

As seen in Fig. 1, the clamping plate may be tightened sufficiently upon the blade to cause a slight reverse flexure at its edges. This flexure may be varied somewhat by adjusting handle 3 to alter the position of 55 the clamping plate, and has the effect of positioning the cutting edges of the blade more nearly to the most effective shaving angle. However, in all adjustments of the razor it is intended that the clamping plate 60 firmly press the corners of the blade against tongues 6 to blank the corners so that they cannot cut or abrade the face of a user.

The razor of Figs. 4, 5 and 6 is formed the same as that just explained as far as 65 concerns the supporting of the blade at its

corners upon tongues which lie above the planes of the guards, and also as far as concerns the provision of a passageway and chamber for receiving shaving refuse. These features are clearly illustrated in the 70 drawings and require no further description. The razor differs from that of Figs. 1, 2 and 3 in that it is a folding razor embodying certain novel features of construction having advantages which will now be explained. 75

The razor includes a guard plate 9 and a clamping plate 10, between which plates a double-edged transversely-flexed blade 11 is clamped. The ends of the clamping plate are provided with rearwardly projecting lugs 12 having outwardly disposed pintles 13 at their outer edges on which offset foldable handles 14 and 15 are pivoted. In Fig. 4 handle 14 is shown in the position it occupies when the razor is in use, and handle 15 is shown folded upon the razor. Normally both handles are in either one of these two positions. The ends of guard plate 9 are provided with recesses 16 formed to receive the lugs 12, and these lugs are turned inwardly and are sufficiently resilient that the clamping plate may be snapped into position between the lugs and when in such position will be firmly engaged by them. To remove the guard plate it is only necessary to press outwardly upon one or the other of its ends which project beyond the clamping plate. This affords a simple means of attaching the guard to the clamping plate in a razor which may be economically manufactured. 90

A further feature of the invention has to do with the forming of the guard plate so that when the razor is in use the guard plate, moving in advance of the edge of the razor, will sufficiently stretch the skin to facilitate shaving. To this end the outer edges of the guard plate which project beyond the blade are roughened, as for example by being knurled in the manner indicated at 17 on Fig. 6. 105

It is characteristic of each embodiment of the invention that the cutting edge of the blade is as freely presented against the face of a user as is the edge of the common unprotected straight razor blade, thus rendering the safety razor capable of effecting a clean close shave. Furthermore, the corners of the blade are so blanked or protected by being held rigidly between the clamping plate and the tongue on the guard as to eliminate the possibility of their causing cuts and abrasions, and an adequate chamber is formed to receive shaving refuse, which chamber is open on all four sides to permit free passage of water through the razor for removal of such refuse. In addition to these advantageous features, the foldable razor of Figs. 4, 5 and 6 is so constructed that it may be quickly and easily 110 115 120 125 130

assembled and disassembled, and that it may be manufactured at a low cost.

According to the provisions of the patent statutes, I have described the principle and 5 operation of my invention, and have illustrated some features of it in its applicability to two forms of razors. However, I desire to have it understood that, within 10 the scope of the appended claims, the invention may be practiced with other forms of construction than those particularly shown and described.

I claim as my invention:

1. A safety razor comprising a guard 15 plate having guards at its opposite sides and provided with tongues at its corners projecting above the planes of the guards and having a medial blade-supporting projection, a clamping plate, and a trans- 20 versely flexed blade arranged between the guard and clamping plate and resting at its central portion on said projection and at its corners on said tongues, the blade being held rigidly at its corners between 25 the clamping plate and said tongues on the guard plate to prevent cutting by the corners of the blade, and the cutting edges of the blade being spaced from the guard intermediate the corners of the blade.
2. A safety razor comprising a flat guard 30 plate having guards at its opposite sides and provided with tongues at its corners projecting above the planes of the guards

and having midway between its guards a blade support projecting abruptly above 35 the plane of the plate, a clamping plate, and a transversely flexed blade arranged between the guard and clamping plates and resting at its central portion on said projection and at its corners on said tongues, 40 the blade being held rigidly at its corners between the clamping plate and said tongues on the guard plate to prevent cutting by the corners of the blade, and its cutting edges being spaced from the guards 45 intermediate the corners of the blade, there being an open ended refuse-receiving chamber formed between the flexed blade and flat guard plate at each side of said blade support. 50

3. A foldable safety razor, comprising a clamping plate provided at each end with a rearwardly projecting resilient lug, a removable guard plate adapted to be snapped between said lugs and when in such position 55 being clamped to the guard plate by the lugs, means for positioning a razor blade between the guard and clamping plate, and offset handles pivoted on said lugs and adapted to be folded upon the front of the 60 clamping plate when the razor is not in use and to protect rearwardly of the guard plate for engagement when the razor is in use.

In testimony whereof, I sign my name.
JACOB G. CROOKSTON.
